(57) **CLAIM**

The ornamental design for an absorbent article with channels, as shown and described.

DESCRIPTION

FIG. 1 is a perspective view of a diaper with specific channels, with the fastening elements depicted in dotted lines;

FIG. 2 is a front view thereof;

FIG. 3 is a left side view thereof;

FIG. 4 is a rear view thereof;

FIG. 5 is a right side view thereof; and,

FIG. 6 is a bottom view thereof.

The channels are visually distinct from the surface of the absorbent article upon which they are disposed.

The dash-dot broken lines shown in the figures depict environmental structure and portions of the article which form no part of the claimed design.
